[57] CLAIM

The ornamental design for an insect catching device or
the like, substantially as shown and described.

DESCRIPTION

FIG. 1 is an exploded perspective view of an insect
catching device showing my new design;

FIG. 2 is a side elevational view thereof;

FIG. 3 is a side elevational view thereof opposite to the
side shown in FIG. 2;

FIG. 4 is a top plan view thereof;

FIG. 5 is a bottom plan view thereof with the blades of
the device shown in a closed position;

FIG. 6 is a front elevational view thereof;

FIG. 7 is a rear elevational view thereof;

FIG. 8 is a transverse sectional view of one blade
thereof taken along line 8—8 of FIG. 2; and

FIG. 9 is a longitudinal sectional view of one blade
thereof taken along line 9—9 of FIG. 2.

FIG.1

FIG. 2
